UNITED STATES PATENT OFFICE

2,280,189

SAFETY MECHANISM FOR NAILING MACHINES

John A. Duran, Beverly, Mass., assignor to United Shoe Machinery Corporation, Flemington, N. J., a corporation of New Jersey

Application February 7, 1941, Serial No. 377,377

6 Claims. (Cl. 1—32)

This invention relates to means for protecting the operators of such nailing machines as those employed for attaching heels to shoes, from injury caused by the accidental starting of the machine in operation.

In an apparatus of the character of that disclosed in Letters Patent of the United States No. 1,157,688, Glidden, October 26, 1915, a hinged guard is placed in front of the reciprocatory nailing die and its co-operating drivers. When raised, this guard covers the movable parts behind it, so the operator's hands cannot come in contact with them. When lowered, access may be had to the die and drivers to allow them to be inspected or changed. Careless operators may leave the guard down, or even entirely remove it because they feel it slows them in their work. With the movable elements thus exposed, the starting treadle of the machine may be depressed accidentally, causing said machine to go through an operating cycle. The operator's hands might then be caught by the normally guarded moving parts, or his head struck by the descending jack, forced down for the application of preliminary pressure to the work. An object of this invention is to give the operator effective protection against such accidents.

In the attainment of the above object, there is combined with nail-driving mechanism, as a die and co-operating drivers, their shielding guard, means by which the driving mechanism is operated and a treadle or other controlling member for such means, locking members of which there may be two, one connected to the controlling member and the other movable into and out of the path of the first and connected to the guard. This arrangement may be caused to prevent actuation of the treadle and the starting of the machine, when the movable parts are exposed, but will permit operation if these are covered. To render it difficult for the operator to take off the guard, and thus be completely deprived of its protection, I have furnished means for preventing disconnection of the pivoted connections between the locking member and guard, when the elements are assembled. In the particular form of the invention herein disclosed, the guard is pivoted upon the machine-frame, and associated with the treadle, which controls the application of power to the nailing mechanism, is a locking bar. An arm is pivoted upon the frame to move into and out of bar-retaining relation, this arm being joined to the guard by a link. The link-connections are preferably pivoted, and the ends of the links are covered by

the associated elements to prevent ready separation.

The drawing illustrates a single embodiment of the invention, it showing my improved safety mechanism in broken side elevation.

Of the machine of the previously mentioned patent, there appears a frame 10, upon which are guided for vertical reciprocation a crosshead 12, carrying a die-block 14, and a crosshead 16, upon which is mounted a plate having drivers 18 movable in nail-receiving passages in the die-block. From a power-shaft 20, the crossheads 14 and 16 are respectively actuated by connections including toggle levers 22 and 24. In the connections to the crosshead 16, a cam-lever 26 is included, the movement of which is governed by a cam-slot 28 formed in it and guided by a projection 30 from the frame. Power is applied to the shaft 20 through a single-rotation clutch mechanism 32, which is tripped by depression of a treadle 34, fulcrumed upon a spindle 36. Connected to the treadle by a link 38 is a locking bar 40, joined at its opposite extremity to the center of the toggle-lever 22. When the treadle is depressed in the normal operation of the machine, the link 38 lifts a shoulder 42 upon the bar clear of a pin 44 projecting laterally from an arm 46 attached to the spindle 36, this allowing full depression of the treadle to initiate an operating cycle. As a protection to the operator from the power-actuated parts of the nailing mechanism, there is hinged in front of these parts upon a pin 48, lying in a horizontal bore in the frame, a guard 50. When this guard is raised to the position shown in full lines in the drawing, the movable elements are completely shielded from contact with the operator, but it may be swung outwardly and downwardly to give full access to these elements. This relation is indicated in dotted lines.

Considering now what is peculiar to the present invention, a boss 52 projects from the guard 50 and fixed in the boss at one side of the axis and parallel thereto, is a pivot-pin 54. This pivot-pin is joined by a link 56 to a pivot-pin 58 lying in a recess at one side of a stop-arm 60 mounted to swing about the frame-projection 30. When the guard 50 is in its raised relation, a transversely extended surface 62 upon the lower end of the arm 60 lies clear of an upward projection 64 from the stop-bar. It will be seen that under these conditions, upon elevation of the locking bar 40 with its projection 64 by depression of the treadle 34, said bar will be free for movement, so the clutch 32 may be tripped to

start the machine in operation. When, however, the guard is lowered, the pin 54, which is in effect a crank-pin, rotates clockwise, drawing the link 56 to the right. This similarly swings the arm 60 until its surface 62 is just above the top of the projection 64. If there is occasion to remove the guard, excessive movement of the arm in this direction is limited by a shoulder 66 upon the arm. The relation of the elements for the lowered position of the guard is as illustrated in dotted lines in the drawing. Now, if an attempt is made to treadle the machine, the bar 40 cannot rise, so it is impossible to release the clutch for driving engagement. Thus, the operator is positively protected from injury by moving parts of the machine, whether these be in the rising die mechanism and driver mechanism, or the un-illustrated descending jack mechanism. To make it hard for the operator to uncouple the safety connections while the associated elements are in place, the pivot-pin 54 is driven into the boss 52 and the adjacent end of the link 56 lies in a circumferential groove formed between a head 70 upon the hinge-pin 48 of the guard 50 and the outer surface of the boss, the hinge-pin being secured to the boss at 72. The opposite extremity of the link and the pivot-pin 58 are similarly situated between the cam-lever 28 and the arm 60. The retaining nut 74 of the cam-lever 26 may also be pinned at 76 to the frame-projection 30. The difficulty involved in disconnection will usually prevent the operator from tampering with the safety mechanism.

Having described my invention, what I claim as new and desire to secure by Letters Patent of the United States is:

1. In a nailing machine, nail-driving mechanism, a guard movable to shield or give access to said mechanism, operating means for the driving mechanism, a movable controlling member for the operating means, a locking member connected to the controlling member, and a second locking member movable into and out of the path of the first locking member and connected to the guard.

2. In a nailing machine, a nailing die, nail-drivers co-operating therewith, the work-engaging portions of said die and drivers being at all times free for the association with and removal of work therefrom, a guard movable to either shield or give access to the die and drivers below their work-engaging portions, operating means

for the drivers, a movable controlling member for the operating means, and means movable under the influence of the guard to lock the controlling member against movement or to release it for actuation.

3. In a nailing machine, nail-driving mechanism, a guard pivotally mounted to be swung between the operator and the nailing mechanism or lowered to give access to said mechanism, operating means for the nailing mechanism, a movable controlling member for the operating means, and locking means for the controlling member, said means including a locking member and a connecting member pivoted to the locking member and to the guard, there being means for preventing the manual disconnection of the connecting member at its pivots while the associated elements are assembled.

4. In a heel-attaching machine, a frame, a nailing die and reciprocatory drivers mounted upon the frame, a guard pivoted upon the frame and lying normally in front of the die and drivers below the point of application of work thereto, operating means for the drivers, treadle mechanism by which the operating means is controlled, and a locking member for the treadle mechanism pivoted upon the frame and connected to the guard.

5. In a heel-attaching machine, a frame, nailing mechanism including a die and reciprocatory drivers movable upon the frame, a guard pivoted upon the frame in front of the die and drivers, operating means for the drivers, a treadle by which the operating means is controlled, a locking bar movable by the treadle and nailing mechanism, an arm pivoted upon the frame and movable into and out of bar-retaining relation, and a link joining the arm to the guard.

6. In a heel-attaching machine, a frame, a nailing die and reciprocatory drivers mounted upon the frame, a guard pivoted upon the frame in front of the die and drivers, operating means for the drivers, a treadle by which the operating means is controlled, a locking bar co-operating with the treadle, an arm pivoted upon the frame and movable into and out of bar-retaining relation, and a link pivotally connected to the arm and guard, the ends of the link at the pivots being covered and rendered inaccessible by the associated elements to prevent separation.

JOHN A. DURAN.
